CLAIM

We claim the ornamental design for a mobile phone, as shown and described.

DESCRIPTION

FIG. 1 is a front perspective view of a mobile phone showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof; and,

FIG. 9 is an enlarged view of the encircled portion in FIG. 2.

The evenly-spaced broken lines in the figures depict portions of the mobile phone that form no part of the claimed design. The dot-dash broken lines in the figures represent a boundary of the claimed design and form no part thereof.

(Continued)

The dot-dot-dash broken lines in FIGS. 2 and 9 encircle portions of the claimed design that are illustrated in an enlargement and form no part of the claimed design.
